UNITED STATES PATENT OFFICE.

KATIE A. LUTZ, OF CLINTON, MISSOURI.

DRESS-MAKER'S SQUARE.

SPECIFICATION forming part of Letters Patent No. 396,099, dated January 15, 1889.

Application filed April 26, 1888. Serial No. 271,977. (No model.)

To all whom it may concern.

Be it known that I, KATIE A. LUTZ, a citizen of the United States, and a resident of Clinton, in the county of Henry and State of Missouri, have invented certain new and useful Improvements in Dress-Makers' Squares; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of my invention and is a front view thereof. Fig. 2 is a reverse view of the same. Fig. 3 shows the square folded, and Fig. 4 is a detail showing the miter-hinge.

The invention relates to improvements in dress-makers' or tailors' squares; and it consists in the construction and novel combination of parts, as hereinafter set forth.

The object of the invention is to provide a sectional square, of wood or other light material, that may be folded to bring its several sections in a parallel and compact form; and a further object being to provide a miter-hinge the flaps of which extend upon and strengthen the ends of the inner sections. The several hinges, being secured by screws to the surface of the rule-sections, are easily removed, so that a new section may be put in place of one that may be accidentally broken.

Referring to the drawings, A A designate

the two inner sections, and B B the outer sections hinged to the outer or square ends of the sections A. The sections are provided on each side with similar graduations, C, in inches and fractional parts thereof. The inner ends 40 of the sections A are beveled to form a square miter, and the miter-hinge D is secured to the surface of the sections by screws. The hinge D is square in outline, and has its edges in line with the edges of the sections, so that the 45 strain is distributed over a large surface, giving strength to the square at a point most liable to fracture.

E E represent strap-hinges securing the respective sections A B together. The hinges 50 E are placed on the sections on the side opposite to the side upon which the hinge D is secured, so that the sections fold in a reverse manner, bringing the parts closely together.

Having described my invention, what I 55 claim is—

A graduated folding square consisting of the sections A B, the sections A, mitered at one end, the miter-hinge secured to the surface of the sections having its edges in line with the 60 edges of the sections, and the strap-hinges securing the sections A B together and placed on the sides opposite the miter-hinge, substantially as specified.

In testimony whereof I affix my signature in 65 presence of two witnesses.

KATIE A. LUTZ.
